(57) **CLAIM**

The ornamental design for an electrical connecting plug, as shown and described.

DESCRIPTION

FIG. 1 is a perspective view of an electrical connecting plug according to the present invention;

FIG. 2 is a top plan view of the electrical connecting plug according to the present invention;

FIG. 3 is a bottom plan view of the electrical connecting plug according to the present invention;

FIG. 4 is a front elevation view of the electrical connecting plug according to the present invention;

FIG. 5 is a rear elevation view of the electrical connecting plug according to the present invention;

FIG. 6 is a right side elevation view of the electrical connecting plug according to the present invention; and,

FIG. 7 is a left side elevation view of the electrical connecting plug according to the present invention.
